UNITED STATES PATENT OFFICE.

RODERICK McCLURE AND CLAUDE OWENS, OF FORT LARAMIE, WYOMING; SAID OWENS
ASSIGNOR TO SAID McCLURE,

COMBINED BENDING AND CUTTING MACHINE.

1,272,068.

Specification of Letters Patent.

Patented July 9, 1918.

Application filed September 25, 1917. Serial No. 193,130.

To all whom it may concern:

Be it known that we, RODERICK McCLURE and CLAUDE OWENS, citizens of the United States of America, and residents of Fort

5 Laramie, in the county of Laramie and State of Wyoming, have invented certain new and useful Improvements in Combined Bending and Cutting Machines, of which the following is a specification.

10 This invention relates to combined bending and cutting machines and has for its object the provision of novel means whereby a single machine of comparatively simple and inexpensive construction may be utilized as a bending machine and as a cutting mechanism for metal or other bars, the said invention having for its object the provision of novel means whereby a plunger coacts with a die for bending the material and

15 20 whereby the said plunger likewise coacts with the stationary member to comprise a cutting mechanism which will sever bars of different sizes into appropriate lengths.

A further object of this invention is to 25 provide a plunger having means whereby it may be reciprocated through manually operated means which requires relatively small power in proportion to the work and results attained by the movement of the

30 plunger.

With the foregoing and other objects in view, the invention consists in the details of construction, and in the arrangement and combination of parts to be hereinafter more 35 fully set forth and claimed.

In describing the invention in detail, reference will be had to the accompanying drawings forming part of this specification wherein like characters denote corresponding 40 parts in the several views, and in which—

Figure 1 illustrates a longitudinal sectional view of a device embodying the invention;

45 Fig. 2 illustrates a top plan view; and Fig. 3 illustrates a section on the line 3—3 of Fig. 2.

In these drawings 5 denotes a bed plate and 6 a jaw or bumper or abutment, which 50 may be formed integral with or secured to the base, the said member 6 having a seat or recess 7 in one face to receive a die 8, it being understood that the dies may be provided with shaping jaws 9 of different 55 configurations according to the work to be

performed and they may be interchangeable so that the one machine may be used for producing different results.

The bed plate 5 is preferably provided with recesses 10 which constitute seats for 60 anti-friction members 11, such as rollers and a plunger 12 extends longitudinally of the bed plate and rests on the anti-friction members so that it may be moved to operate with the die.

65 The plunger is held in operative position and guided by or between standards 13, 14, 15 and 16, which rise from the bed plate and which may be integral with it or secured to it in any way, a preferred construction being that the bed plate be dovetailed transversely as at 17 and 18 and the standards carried by the plates 19 and 20 which fit in the dove-tails 17 and 18 respectively, since by this arrangement, the 70 parts may be disassembled and reassembled and if a part becomes impaired or broken, it can be renewed without undue expense.

75 The pairs of standards 13 and 14 are spaced apart and anti-friction rollers 21 80 and 22 are interposed, which anti-friction rollers are mounted on members such as bolts 23 which are supported on the said standards. The standards 15 and 16 are also spaced apart and an anti-friction roller 24 is 85 interposed and supported by a member 25 such as a bolt extending through the standards 15 and 16.

80 The anti-friction members 21, 22 and 24 engage the upper edge of the plunger, thus 90 preventing vertical movement of the plunger when being operated to bend material or cut it. Near the end of the plunger remote from the die, the said plunger has a recess 26 which constitutes a seat for a cam 27, 95 which cam is mounted on a pivot 28 extending between and supported by the standards 15 and 16. The said cam has an operating handle 29 which may be manipulated by an operator and the cam is intended 100 to act with the walls of the recess 26 to move the plunger inwardly or outwardly according to the direction of rotation of the cam.

105 In order to utilize the plunger as one member of a cutting mechanism, the upper edge preferably of the said plunger has seats or recesses 30 and 31 of different dimensions or sizes so that it will receive the material or bars of different sizes and the 110

walls of these recesses are preferably beveled slightly so that their edges will perform a shearing action when coacting with the stationary member constituting another 5 element of the cutter to be presently explained. It is obvious that the recesses 30 and 31 may be multiplied or diminished within predetermined bounds so that they may be utilized in connection with materials of different cross sectional dimensions. 10

The combined cutter and plunger coacts as an element of the cutter with a stationary blade or bar 32 which has recesses 33 and 34, the additional recesses corresponding to the 15 recesses of the plunger, and this stationary member may be held between the standards 13, 14, 15 and 16 so that the plunger slides or reciprocates along the side of the stationary member. 20

The operation of the device of the elements thereof has been indicated in connection with the description of the construction of the several elements and their relation to other elements and a résumé of the 25 mode of operation is believed to be unnecessary, as it is thought that one skilled in the art will be able to practice the invention from the foregoing description and the illustration. 30

We claim:

1. In a combined bending machine and cutter, a base having an abutment near one end, a die bearing against the said abutment, said base having recesses therein, anti-friction members in the said recesses, a plunger movable on the antifriction members, said plunger having recesses in its upper edge, the walls of the said recesses being diagonally disposed, means for guiding the plunger with relation to the die, said plunger having a recess near one end, a cam pivotally mounted to operate in the last mentioned recess and adapted to coact with the walls of the recess for moving the plunger, and a 40

stationary member having recesses corresponding with the recesses of the plunger and adapted to receive material to be cut by the operation of the plunger. 45

2. In a combined bending machine and cutter, a base having an abutment near one end, a die bearing against the said abutment, said base having recesses therein, anti-friction members in the said recesses, a plunger movable on the anti-friction members, said plunger having recesses in its 50 upper edge, the walls of said recesses being diagonally disposed so as to form cutting edges, means for guiding the plunger with relation to the die, said plunger having a recess near one end, and a cam pivotally mounted to operate in the last mentioned recess and adapted to coact with the walls of the recess for moving the plunger. 55

3. In a combined bending machine and cutter, a base having an abutment near one 60 end, a die bearing against the said abutment, said base having recesses therein, anti-friction members in the said recesses, a plunger movable on the anti-friction members, said plunger having recesses in its 65 upper edge, the walls of said recesses being diagonally disposed so as to form cutting edges, means for guiding the plunger with relation to the die, said plunger having a recess near one end, a cam pivotally mounted 70 to operate in the last mentioned recess and adapted to coact with the walls of the recess for moving the plunger, and pairs of standards rising from the base comprising guides for the plunger, anti-friction members between the said standards bearing on the 75 upper edge of the plunger, means extending between the pairs of standards for supporting the anti-friction members, and means for rotating the cam. 80

RODERICK McCLURE.
CLAUDE OWENS.
